UNITED STATES PATENT OFFICE.

WILLIAM BIRCHALL, OF WHITWORTH, NEAR ROCHDALE, ENGLAND.

VACUUM STRIPPING APPARATUS.

1,160,825.

Specification of Letters Patent. Patented Nov. 16, 1915.

Application filed February 2, 1914. Serial No. 816,068.

To all whom it may concern:

Be it known that I, WILLIAM BIRCHALL, a British subject, residing at Whitworth, near Rochdale, county of Lancaster, England, have invented certain new and useful Improvements in Vacuum Stripping Apparatus, of which the following is a specification.

This invention relates to improvements in 10 vacuum stripping apparatus for carding engines or other similar machines.

It consists essentially of mechanism whereby when the stripping operation is started at the first of a series of carding engines, or 15 other similar machines, the stripping mechanism of each succeeding machine will be automatically put into operation at or near the conclusion of the stripping operation of the preceding machine.

20 The invention will be fully described with reference to the accompanying drawings forming part of the specification in which it is shown applied to a carding engine.

Figure 1. is a front view of the mechanism 25 showing sufficient of the stripping apparatus to illustrate the invention. Fig. 2. is a plan of same. Fig. 3 is a plan view of a lever system which co-operates with the traversing mechanism. Figs. 4 and 5 are detail plan 30 views of the setting on mechanism. Fig. 6. is a diagrammatic plan showing the setting on rods of the three machines of a series, the valves of all three being closed. Fig. 7. is a similar view showing the valve of the first 35 machine moved into the open position to commence stripping. Fig. 8. is a similar view showing the valve of the second machine opened and the valve of the first machine closed after the termination of the 40 stripping of that machine. Fig. 9 is a detail view showing a traversing mechanism for the nozzle Z'. Fig. 10 is a sectional view on the line 10—10 of Fig. 9.

45 As is usual in vacuum stripping apparatus the stripping nozzle Z' is carried on a traversing carriage Z mounted on a guide X extending across the machine on which is a continuously rotating threaded rod α provided with two opposite and intersecting 50 screw threads with which a pin or projection α on the carriage Z engages to cause the latter and with it the nozzle Z' to traverse the machine, the guide X having a longitudinal slot α' through which the projection α extends. The nozzle Z' is connected with

the main vacuum pipe C' by the branch pipe C and the flexible pipe C'.

A shaft A (preferably vertical) is carried on a suitable footstep or bracket D attached to the frame L' of the machine and its upper end is connected to a valve B placed in the branch vacuum pipe C, the valve B being operated by the rotation of the shaft A and controlling the suction of the nozzle Z'. A double armed lever E is mounted fast upon the lower end of the shaft A and each end of the lever E is connected to a rod or lever F or F' provided with fingers or forked ends G, G' respectively adapted to be engaged by or engage the nozzle carriage Z at one or other end of the guide X. Thus when the carriage Z is at the end of its traverse it will engage one of these fingers and move it forward causing the lever system F, E, F' to be moved with it and the shaft A rotated. 75 The fingers G, G' being connected to opposite ends of the lever E move inward and outward together (i. e., simultaneously toward or simultaneously away from one another) consequent to pivotal movement of 80 said lever. The nozzle Z' will be traversed in one direction for the first stripping, in the reverse direction for the second, and so on.

A three armed lever H is affixed to the 85 shaft A near its upper end and is pivoted at one end to the end J' of a connecting rod j extending to the next machine where its end J is operated by the corresponding three 90 armed lever H as similar mechanism is employed for each carding engine in the series, as shown in Figs. 6, 7 and 8. The end J of the connecting rod or lever j is provided with a projection K which engages with a 95 catch or projection K' on the lever H so that when the shaft A and with it the lever H are rotated the projection K' engages with the projection K and pushes the rod j forward. An arm M forms part of the lever 100 H and carries at its end a runner or roller L which engages the side of the rod j when the lever H has rotated a certain distance and moves the rod j so that the projection K is moved and held out of engagement 105 with the projection K' thus allowing the rod j to return to its normal position. A lever N is pivoted to the lever H at or near its end and carries a runner or roller O which bears 110 against the opposite side of the rod j to the roller L. The arm N is attached to a weight

P by a chain P' passing over a guide pulley R so that the catch K is held in engagement with the catch K' until the rod j is moved by the roller L.

The invention has been described with reference to a vacuum stripping mechanism in which the nozzle (or nozzles) are traversed by a rotary rod with screw threads in opposite direction but it can be applied to any other form of traversing motion.

The stripping mechanisms of the several machines come into operation successively. In the embodiment disclosed, the first machine to be operated is the one at the left end of the series or gang of machines and the successive operations of the stripping mechanisms proceed from the left end of the series or gang of machines toward the right end thereof. In one operation of all the stripping mechanisms the stripping nozzles will move from left to right. In the next succeeding operation, although the machines are to be stripped in the order of their arrangement, from left to right, the stripping nozzles will move from right to left.

Figs. 6, 7 and 8 show diagrammatically the operating connections between the first and second and between the second and third machines of a gang or series. According to Fig. 6, the said connections are shown in the positions which they occupy when all of the valves B of the mechanisms to which said connections relate are closed. According to Fig. 7, the valve B of the first machine has been opened and the valves B of the second and third machines are closed. According to Fig. 8, the valve B of the second machine has been opened and the valves B of the first and third machines are closed.

The operation of the mechanism is as follows:—The shaft A of the first machine to be stripped is rotated by hand or other means to cause the finger G to bring the nozzle carriage Z into engagement with the traversing mechanism X and at the same time to open the valve B of the first machine of the series, the lever H being moved from the position of Fig. 6 to the position of Fig. 7. The nozzle of the first machine then traverses to the opposite side of the guide X and engages the finger G' thereby rotating the shaft A of the first machine in the opposite direction and restoring it to its initial position. This rotation of the shaft A closes the valve B of the first machine and rotates the lever H so that the projection K' thereon which engages the projection K on the end J of the rod j moves the rod j forward. The other end J' of the rod j is affixed to the end of the corresponding lever H of the succeeding or second carding engine so that the movement of the said lever H from the position of Fig. 7 to the position of Fig. 8 causes the shaft A of the sec-

ond machine to be rotated, the valve B to be opened and the nozzle carriage Z to be moved into engagement with the traversing mechanism. The stripping mechanism of the next machine is thus brought into operation and the movement is transmitted in turn in a similar manner to all the machines in the series. At the next stripping operation since the fingers G G' move inward and outward together the stripping nozzles will be traversed in the opposite direction. (See Fig. 3.) The next stripping operation or series of operations is initiated in like manner, the shaft A of the first machine to be stripped, i. e. the machine at the left end of the gang or series in the embodiment shown, being rotated by hand or other means to cause the finger G' to bring the nozzle carriage Z into engagement with the threaded shaft of the traversing mechanism. The operation is transmitted from one machine to the other in the same manner as above described. In this connection it may be noted that the pin z of the traversing mechanism is formed as a fork within the carriage Z and is mounted to rotate in said carriage, one prong of the fork being longer than the other. When the carriage is moved inward by the lever F, the screw x being in rotation, will engage the long prong of the fork of the pin z, knocking it to one side, and thereby bringing the short prong into engagement with the screw.

What I claim as my invention and desire to protect by Letters Patent is:—

1. The combination with a series of carding engines or other machines of a vacuum stripping mechanism for each machine comprising a stripping nozzle and traversing mechanism therefor and mechanism connected to the stripping mechanism of the next machine to put automatically into operation the stripping mechanism of the latter when the stripping of the first machine is nearly or quite concluded.

2. The combination with a series of carding engines or other machines of vacuum stripping mechanism for each machine comprising a stripping nozzle, traversing mechanism therefor, and a valve to which said nozzle is connected, a vertical shaft by which the operation of said valve is controlled, connections for partially rotating said shaft and for operation thereby and arranged to engage or to be engaged by the nozzle carriage upon the completion of the movement of said carriage in either direction, and other connections between each of said vertical shafts and the vertical shaft of the next succeeding machine whereby the vertical shaft of one machine will automatically effect an operation of the shaft of an adjoining machine.

3. The combination with a series of carding engines or other machines of a stripping

mechanism for each machine comprising a stripping nozzle, a nozzle carriage, a mechanism for moving said carriage from one end of the machine to the other and a valve to which said nozzle is connected, a vertical shaft controlling the operation of said valve, a two-armed lever on the lower end of said shaft, links connected to the ends of said lever and having forks adjoining the ends of 5 the machine to engage and for engagement by said nozzle carriage, and connections whereby the vertical shaft of one machine when operated through said links and said lever by said nozzle carriage upon the completion of the movement of the latter in one direction will effect a rotation of the vertical shaft of the succeeding machine.

4. The combination with a series of carding engines or other machines of a stripping 20 mechanism for each machine comprising a stripping nozzle, a nozzle carriage, a mechanism for moving said carriage from one end of the machine to the other and a valve to which said nozzle is connected, a vertical shaft controlling the operation of said valve, a two-armed lever on the lower end of said shaft, links connected to the ends of said lever and having forks adjoining the ends of 25 the machine to engage and for engagement by said nozzle carriage, and connections 30

whereby the vertical shaft of one machine when operated through said links and said lever by said nozzle carriage upon the completion of the movement of the latter in one direction will effect a rotation of the vertical shaft of the succeeding machine, comprising a three-armed lever on said vertical shaft, a rod pivotally connected to one arm of said three-armed lever, the second arm of 35 said three-armed lever having a catch, said rod having a projection near its free end and the said projection engaging the catch of the three-armed lever of an adjoining machine, the third or intermediate arm of said three-armed lever having a projection for the purpose of lifting the rod extending from the three-armed lever of the adjoining machine from engagement with said catch, and yieldable means acting on the free end portion of each rod to hold the same against the catch 40 of the three-armed lever which said rod engages.

In testimony whereof I have hereunto set my hand in presence of two subscribing witnesses.

WILLIAM BIRCHALL.
